CLAIM

I claim the ornamental design for a lady's shaver, as shown and described.

DESCRIPTION

FIG. 1 is a front elevational view of a lady's shaver showing my new design;

FIG. 2 is a left side elevational view thereof, the right side being a mirror image thereof;

FIG. 3 is a rear elevation thereof;

FIG. 4 is a bottom plan view thereof; and,

FIG. 5 is a top plan view thereof.

1 Claim, 1 Drawing Sheet
